Des. 208,586
Patented Sept. 12, 1967

208,586

EYEGLASS CASE

Joseph M. Gindi, 984 E. 8th St.,
Brooklyn, N.Y. 11230

Filed Apr. 5, 1966, Ser. No. 1,785

Term of patent 14 years

(Cl. D57—1)

FIG.1

FIG. 3

FIG. 4

FIG. 2

FIG. 5

FIG. 1 is a front elevational view of an eyeglass case, showing my new design;

FIG. 2 is a side elevational view thereof; with the eyeglass case shown in an open position, the other side being identical;

FIG. 3 is a rear elevational view thereof;

FIG. 4 is a top plan view thereof; and,

FIG. 5 is a perspective view of the eyeglass case in an open condition.

I claim:

The ornamental design for an eyeglass case, as shown and described.
